A. Gerould and J. H. Ward of Middletown, Conn.,
Letters Patent, No 589, Dated August 2nd 1853.

The Schedule referred to in these Letters Patent and making
part of the same.

To all whom it may concern:

Be it known that we, Allen Gerould and John H. Ward, both of Middletown in the County of Middlesex and State of Connecticut, have invented or produced a new and original design for the instrument known as the "Sewing Bird", and we do hereby declare that the following is a full and exact description of the same, reference being made to the accompanying drawings as a part of this specification.

Figure I. is a side elevation of the Instrument

Figure 2. is a top view of the same representing the bird in a sitting position;

What we claim and desire to secure by Letters Patent, is the design herein represented of an entire bird in a sitting posture, constituting an ornamental design for a sewing bird.

Dated at Middletown the 19th day of July

A. D. 1853.
